UNITED STATES PATENT OFFICE

THEODORE S. JUSTUS, OF CHICAGO, ILLINOIS

HAIR CURLER

Application filed April 1, 1929. Serial No. 351,507.

The invention relates to hair curlers and particularly to that type where a spring band is bent into a loop and the free ends are interlocked so as to apply a pressure to strands of hair arranged between the legs of the curler to produce a wave effect for the hair.

Hair curlers hitherto produced have the disadvantage that the free ends of the spring bands are interlocked in such a manner that 10 opening thereof becomes difficult, especially where hair strands are caught between the ends.

To obviate this difficulty the present invention has for its principal object the provision 15 of a curler which is of simple construction and may be easily manipulated so as to close or open the hair curler without any difficulty.

A further object consists in providing the curler band with an extension at one end to 20 permit loose ends of the hair strands to be held in place while the curler is wound.

Other and equally important objects will 25 become apparent from a perusal of the invention, the latter comprises the means described in the following specification, particularly pointed out in the claims forming a part thereof, and illustrated in the accompanying drawing, in which

Figure 1 is a perspective view of a hair 30 curler constructed in accordance with my invention.

Figure 2 is an end view of the curler.

Figure 3 is a side view, and

Figure 4 is a section on the line 4—4 of 35 Figure 3.

The curler comprises a spring band designated by 10, which comprises a main body portion 11 and an end portion 12, said portions being interconnected by a small loop 13 40 to impart resiliency to the band. The body portion 11 is provided with a slide member 14 and at its extremity is equipped with a loop 15 and with an extension 16 bent to engage the outside of the body portion 11, and 45 being bent to comprise a portion 17 parallel

to the body portion 11 and which end portion 18 is curved by contact with the body portion.

In use a strand of hair is coiled around the body portion 11 whereupon the end portion 12 is forced into contact with the body portion 11 and the slide 14 is shifted so as to encompass the extremity of the end portion 12. When it is desired to remove the curler then the slide is shifted so as to release the end portion 12 and the curler may be readily removed from the hair. Loose strands may be secured in place by introducing them between the body portion 12 and the extension 16. The curler when wound holds the hair in place and affords a neat appearance as no loose hair ends are visible.

Furthermore the convenient manner of securing the free end 12 in place or releasing the same facilitates the manipulation of the curler and avoids the possibility of damage to the finger nails when opening or closing the curler. The disadvantage of injury to the finger nails is entirely obviated with the present invention without in any way adding to the cost of producing the curler.

While the drawing shows a preferred embodiment of the invention, numerous changes may be made without departing from the spirit of this invention. I, therefore, do not limit myself to the details of construction 75 nor to the arrangement of parts as shown, but wish to include all changes, alterations, revisions and modifications constituting departures within the scope of the invention as defined in the appended claims.

I claim:

1. A device of the character described, including a spring band bent intermediate its ends to provide two legs with the free ends tending to separate from one another, and 85 a sleeve on one leg adapted to receive the free end of the other leg, said sleeve carrying leg being extended and folded upon itself to provide means for securing loose strands of 90

hair and normally retaining said sleeve in idle position.

2. A device of the character described, including a spring band bent intermediate its ends to provide two legs with the free ends tending to separate from one another, and a sleeve on one leg adapted to receive the free end of the other leg, said sleeve carrying leg having an extension folded upon itself but spaced intermediate its ends to permit shifting of said sleeve and normally retaining said sleeve in idle position.

In witness whereof I affix my signature.

THEODORE S. JUSTUS.
